CLAIM

The ornamental design for a display screen or portion thereof with graphical user interface, as shown and described.

DESCRIPTION

FIG. 1 is a front view of a display screen or portion thereof with graphical user interface showing my new design; FIG. 2 is an enlarged view of indicated portion (marked as number 2) of FIG. 1; and, FIG. 3 is an enlarged view of indicated portion (marked as number 3) of FIG. 1.

The outermost dot-dot-dash broken line showing of a display screen or portion thereof, as well as the broken line showing of elements of the graphical user interface illustrate portions of the article and do not form part of the claimed design. The dot-dash broken lines of FIG. 1 illustrate the boundaries of the portions of the design from which FIGS. 2 and 3 have been taken and enlarged.

Each of the views would also represent what a user will see when he/she wears a virtual reality device.
